UNITED STATES PATENT OFFICE

172,535

EMBOSSED TEXTILE FABRIC

George P. Feindel, Rock Hill, S. C., assignor to
Rock Hill Printing & Finishing Company, a cor-
poration of Delaware

Application November 18, 1953, Serial No. 27,652

Term of patent 14 years

(Cl. D92—1)

To all whom it may concern:

Be it known that I, George P. Feindel, a citizen of the United States, residing at Rock Hill, in the county of York and State of South Carolina, have invented a new, original, and ornamental Design for an Embossed Textile Fabric, of which the following is a specification, reference being had to the accompanying drawing, forming part thereof, in which the figure is a plan view of an embossed textile fabric, showing my new design.

A design unit is outlined by dotted lines and is repeated as indicated.

This application is a continuation-in-part of

my copending application D. 27,435, filed November 3, 1953.

I claim:

The ornamental design for an embossed textile fabric, substantially as shown and described.
